UNITED STATES PATENT OFFICE

WILLIAM G. NAISMITH, OF DENVER, COLORADO, ASSIGNOR, BY MESNE ASSIGNMENTS, TO THE GARDNER-DENVER COMPANY, OF QUINCY, ILLINOIS, A CORPORATION OF DELAWARE

TOOL RETAINER

Application filed November 19, 1926. Serial No. 149,480.

The object of the present invention is to provide an effective retainer of a novel character that will withstand hard usage.

The preferred embodiment of the invention is illustrated in the accompanying drawings, wherein:

Figure 1 is a side elevation of the chuck of a drilling apparatus, showing the retainer in place thereon, and in its operative position,

Figure 2 is a view similar to Figure 1, but showing the retainer swung to its inoperative position.

Figure 3 is an end elevation,

Figure 4 is a longitudinal sectional view, Figure 5 is a cross sectional view on the line 5—5 of Figure 4,

Figure 6 is a detail view in elevation, showing the position of the retainer when the retainer spring is being placed,

Figure 7 is a view in elevation of the chuck with the other parts removed,

Figure 8 is a sectional view on the line 8—8 of Figure 7,

Figure 9 is a perspective view of said chuck, Figure 10 is a perspective view of the tool retaining yoke and the carrier blocks.

A chuck is shown at 11, and is adapted to be mounted on the front end of suitable drilling apparatus. A portion of said drilling apparatus is shown in Figure 4 and includes a barrel 12 and a hammer 13 that operates on a drill steel as 14, placed in the chuck 11. This steel is provided with a collar 15. It is believed that the type of tool will be readily understood to those skilled in the art.

The chuck 11 is provided on opposite sides with substantially U-shaped guideways, each having spaced side walls 16 and 17, the side wall 17 being preferably longer than the side wall 16, and having a terminal enlargement 18 with a beveled end, constituting an abutment shoulder 19. Slidable in these guideways are carrier members in the form of blocks 20, having thereon outstanding gudgeons 21. The front ends of these blocks are curved, as illustrated at 22, the curvature preferably having a radius with an axis coincident to the axis of the gudgeons. The chuck is furthermore provided on opposite

sides of the guideways with stop lugs 23, and has in its front end a peripheral annular groove 24.

The tool retainer is in the form of a yoke 25, adapted to embrace the drill steel 14 in advance of the collar 15, and has its interior area of less diameter than the diameter of the collar, so that when in place, as shown in Figures 1, 3 and 4, the tool cannot become dislodged from the chuck. This yoke preferably has on opposite sides of its open portion inwardly extending lugs 26 that are adapted to engage over the collar 15 when the collar is against the yoke, and thus prevent any tendency of the yoke to open. The yoke has rearwardly extending side arms 27 provided with openings 28 that receive the gudgeons 21. Consequently the yoke is pivotally mounted on the carrier blocks 20. Said side arms further have inwardly extending lugs 29 that slidably bear against the curved front shoulders 22 of the carrier blocks, and when the yoke is swung to open position to release the drill steel, these lugs 29 abut against the shoulders 19 of the enlargements 18 of the guideways, and serve to limit the outward swinging movement of the yoke. The yoke, however, can swing in an opposite direction, and to a greater degree than its opening movement, when there is no drill steel in the chuck, as will be evident by reference to Figure 6.

Surrounding the chuck is a coiled spring 30, the rear end of which bears against the lugs 29. Its front end is abutted against a holding collar 31, fitted upon the front end of the chuck. This holding collar has an internal groove 32 that overlies and alines with the annular groove 24 in the chuck. In these grooves is seated a split holding ring 33 that thus serves to effectively lock the collar against outward movement.

With this construction, when a steel is in place and the yoke is in operative position, the steel can have a limited longitudinal movement in the chuck, which movement is limited by the yoke, but cannot become detached therefrom. It will be noted in connection with this, that the spring 30 bears against the lugs 29 and the lugs 29, in turn, bear

against the gudgeon blocks 20. As a consequence many of the shocks and jars, especially on the rearward movement of the yoke, are transmitted directly to the blocks 20, and by them against the rear ends of the guideways, thus relieving the gudgeons of the same. When the yoke is swung to open position, the spring then bears against the beveled ends of the lugs 29, and holds the yoke in such position against the stop shoulders 19. When there is no drill steel in the chuck, the yoke can be swung to an opposite inclination, as indicated in Figure 6, in which case the spring 30 will bear against the stop lugs 23. This is a desirable relation of parts when assembling the retainer. In other words, the blocks 20 are first engaged with the yoke and put in the guideways, after which the spring 30 is placed in position, the yoke being in the position shown in Figure 6. The holding collar 31 is then slipped over the end of the chuck and passed beyond the groove 24 of said chuck. By allowing the spring to slip downwardly against the lugs 23, it does not have to be so greatly compressed. The split retaining ring 33 is then snapped into the groove 24, and the holding collar allowed to slide forwardly until it covers the spring, as shown in Figure 4, whereupon the device is assembled and the yoke can then be swung to the opposite position in order to permit a steel being placed in the chuck.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

What I claim is:

1. The combination with drilling apparatus having a holder for a tool to be operated on and having guideways on its opposite sides, of separate carrier members slidably mounted in the guideways, a spring surrounding the tool holder and acting on both carriers, and a tool retaining yoke having pivotal connections with both members.

2. The combination with drilling apparatus having a tool holding chuck, said chuck being provided with longitudinal guideways on its opposite sides, of gudgeon carriers slidably mounted in the guideways, a yoke having side arms journaled on the gudgeon carriers, and a coiled spring surrounding the chuck in advance of the carriers and operating against the same.

3. The combination with drilling apparatus having a tool holding chuck, said chuck being provided with longitudinal guideways on its opposite sides, of gudgeon carriers slidably mounted in the guideways, a yoke hav-

ing side arms journaled on the gudgeons carriers, and a coiled spring surrounding the chuck in advance of the carriers and abutting against the same, said chuck having an annular groove in its front end, a collar surrounding the chuck, overlying the groove and having an internal groove, and a retaining ring in said groove, said collar constituting an abutment for the spring.

4. The combination with drilling apparatus having a holder for a tool to be operated on, of a guideway on the apparatus, a carrier member slidably mounted in the guideway, and a tool retaining yoke having a pivotal mounting on the carrier member and having an abutment against the carrier member in addition to said pivotal mounting to relieve the latter from shocks imparted to the yoke.

5. The combination with drilling apparatus having a holder for a tool to be operated on, of a guideway on the apparatus, a carrier member slidably mounted in the guideway and having an abutment shoulder, and a tool retaining yoke having a pivotal mounting on the carrier member and having a fixed shoulder slidably engaged with the shoulder of the carrier to relieve the pivot mounting from shocks imparted to the yoke.

6. The combination with drilling apparatus having a holder for a tool to be operated on, of a guideway on the apparatus, a carrier block slidably mounted in the guideway and having a fixed abutment shoulder, and a retaining yoke having an arm pivoted to the block and having an inset lug that slidably bears against the shoulder.

7. The combination with drilling apparatus having a holder for a tool to be operated on, of guideways on opposite sides of the same, carrier blocks slidably mounted in the guideways, and a tool retaining yoke having side arms that are pivotally engaged with the blocks and having sliding bearings against the ends of the blocks.

8. The combination with drilling apparatus having a holder for a tool to be operated on, of guideways on opposite sides of the same, carrier blocks slidably mounted in the guideways, a tool retaining yoke having side arms that are pivotally engaged with the blocks and having sliding bearings against the ends of the blocks, and a spring surrounding the tool holding means and having bearings against the portions of the arms that slidably bear against the blocks.

9. The combination with drilling apparatus having a chuck for holding a tool to be operated on, of a tool retaining yoke pivotally mounted on the chuck, a spring that normally bears against the yoke to resist its movement, a removable abutment for the spring, and a stop for the portion of the spring that bears against the yoke, said spring when bearing against the yoke being out of engagement with the stop and said

yoke being movable to a position to permit the spring to bear against the stop.

10. The combination with drilling apparatus having a chuck for holding a tool to be operated on, of guideways on opposite sides of the chuck, each having spaced walls, carrier blocks slidably mounted in the guideways, a tool retaining yoke pivoted to the blocks and having shoulders that bear against the ends of the walls when the yoke is swung, and a spring surrounding the chuck and bearing against the shoulders of the yoke. 70

10

and a spring surrounding the chuck and bearing against the shoulders of the yoke.

11. The combination with drilling apparatus having a chuck for holding a tool to be operated on, of guideways on opposite sides of the chuck, each having spaced walls, one of said walls being longer than the other, carrier blocks slidably mounted in the guideways, a tool-retaining yoke having side arms pivoted to the carrier blocks and having shoulders that bear against the blocks and the ends of the longer walls when the yoke is swung in one direction, a spring surrounding the chuck and bearing against the shoulders of the yoke, stop lugs for the spring carried by the chuck and so disposed that the spring will bear against them when the yoke is swung over the shorter walls, and a front abutment for said spring, removable and replaceable when the spring is against said stop lugs. 80

25

12. The combination with drilling apparatus having a tool holder, of a carrier slidably mounted on the tool holder, a tool retainer pivotally mounted on the carrier, a spring mounted on the tool holder for resisting the sliding movement of the carrier and retainer, and an abutment for the spring carried by the retainer at one side of its pivot axis. 85

30

13. The combination with drilling apparatus having a tool holder, of a carrier slidably mounted on the tool holder, a tool retainer pivotally mounted on the carrier, a spring mounted on the tool holder for resisting the sliding movement of the carrier and retainer, and an abutment for the spring carried by the retainer at one side of its pivot axis and having a sliding bearing against the carrier. 90

35

14. The combination with drilling apparatus having a tool holder, of a carrier slidably mounted on the tool holder, a tool retainer pivotally mounted on the carrier, a spring mounted on the tool holder for resisting the sliding movement of the carrier and retainer, an abutment for the spring carried by the retainer at one side of its pivot axis and having a sliding bearing against the carrier, and a stop on the tool holder against which the abutment on the retainer strikes to limit the 95

40

pivotal movement of the retainer. 105

45

15. The combination with drilling apparatus having a tool holder, and guideways on opposite sides thereof, of carrier blocks slidably mounted in the guideways, a tool retaining yoke having side arms pivoted to the car- 110
